STUFFED TOY

William G. Pendill, Hinsdale, Ill., assignor to Nutrition Dynamics, Inc., Hinsdale, Ill.

Filed Mar. 15, 1973, Ser. No. 341,350

Term of patent 14 years

Int. Cl. D21—01

U.S. Cl. D34—4 R

The sole figure is a perspective view of a stuffed toy showing my new design, the opposite view being a mirror image.

I claim:

The ornamental design for a stuffed toy, as shown and described.
